UNITED STATES PATENT OFFICE.

ARTHUR SCHIMMEL, OF EVANSVILLE, INDIANA.

FURNACE.

1,191,036.

Specification of Letters Patent. Patented July 11, 1916.

Application filed July 22, 1915. Serial No. 41,297.

To all whom it may concern:

Be it known that I, ARTHUR SCHIMMEL, a citizen of the United States, residing at Evansville, in the county of Vanderburg and State of Indiana, have invented certain new and useful Improvements in Furnaces; and I do declare the following to be a full, clear, and exact description of the invention, such as will enable others skilled in the art 10 to which it appertains to make and use the same.

My invention relates to improvements in furnaces, and more particularly to those of the hot air type, the main object of the invention being to improve upon the construction 15 of devices of this class to such an extent as to provide a heater from which hot air may be directed into a single room or led to a number of rooms, by a novel arrangement of parts.

With this general object in view, the invention resides in certain novel features of construction and in unique combinations of parts to be hereinafter fully described and 25 claimed, the descriptive matter being supplemented by the accompanying drawings wherein:

Figure 1 is a front elevation of a furnace constructed in accordance with my invention; Fig. 2 is a vertical sectional view as seen on the plane designated by the line 2—2 of Fig. 1; Figs. 3, 4, 5 and 6 are horizontal sections as viewed upon the planes designated respectively by the lines 3—3, 35 4—4, 5—5 and 6—6 of Fig. 2; Fig. 7 is a perspective view of one of the ring-like sections of one of the shells; Fig. 8 is a detail top plan view illustrating a modified form of construction to be described; Fig. 9 is a 40 detail vertical section taken on the line 9—9 of Fig. 8; Fig. 10 is a bottom plan view of one of the cover plates disclosed in Figs. 8 and 9.

In these drawings which constitute a part 45 of the application and in which similar reference characters designate corresponding parts throughout the several views, the numeral 1 designates a base frame which preferably comprises a circular ring 2 having an upstanding flange, and a plurality of inwardly extending arms 3 upon which the bottom of the ash pit 4 of the furnace proper rests, the latter being designated broadly by the reference numeral 5. The furnace 5 may 50 be of any preferred formation although the design disclosed is preferable, the device

being shown as provided with a cast metal passageway 6 through which fuel may be fed to the fire-box 7, while the ash pit 4 is provided with an additional passageway 8 60 through which ashes may be removed therefrom, the two passageways 6 and 8 being closed respectively by hinged doors 9 and 10 both of which are preferably equipped with appropriate dampers.

Surrounding and spaced from the furnace proper 5, is an inner shell 11 which is composed of a number of sheet metal sections such as that disclosed at 12 in Fig. 7, said sections being capable of being spread out 70 flat for purposes of packing and transportation, but normally assuming substantially the contour seen in the aforesaid figure, one end of each section being provided with an appropriate crimp 13 which constitutes a 75 seat for the other end, while both ends are provided with apertured ears 15 through which bolts 16 are passed (see Figs. 3, 4, 5 and 6).

Interposed between the several sheet 80 metal sections 12 and each having an external central rib 17 which is disposed between the adjacent edges of such sections, is a plurality of cast metal rings 18, the lowermost of which is supported rigidly by appropriate 85 braces 19 from the base 1.

As most clearly shown in Fig. 2, the uppermost section 12 of the inner shell is positioned a considerable distance above the furnace proper, while the section between 90 the latter and said uppermost section is gradually decreased in size from its lower to its upper end being frusto cone-shaped. Fitting snugly within, or snugly surrounding the upper end of the uppermost section 95 12, as the case may be, is an annular flange 20 which depends from an appropriate grating 21 adapted to be placed over an opening in a floor 22 above the furnace room, whereby heat rising from the furnace may be 100 utilized for heating the room or rooms directly above the aforesaid furnace room. Also depending from the grating 21, but spaced outwardly from and surrounding the flange 20, is an additional continuous flange 105 23 into which the upper end of the uppermost of a plurality of jacket sections 12 projects, the jacket formed by such sections being of a construction practically identical with that of the inner shell, further description being therefore deemed unnecessary, 110 except that it may be stated that the lower-

most section 12^a and the section immediately above the same, are provided with apertured ears 14^a through which appropriate fasteners 15^a are passed, said fasteners being 5 here shown as extended through additional ears 14^b on the opposite edges of the upper and lower cast metal front plates 24 and 25 to which the doors 9 and 10 are respectively hinged, and through which the passageways 10 6 and 8 open.

In addition to the shell and jacket above described, an insulating lining 26 of black iron or other appropriate material is provided, such lining being here shown as composed of a number of ring-like sections whose upper and lower edges are received in hook-shaped keepers 27 formed on the upper and lower edge portions of the rings 18 at the inner sides of the latter. This insulating means is provided in order that cold air may flow downwardly between the shell and the jacket as indicated by the arrows in Fig. 2 and may then pass upwardly within the inner shell to be heated by the furnace 20 proper therein, yet that such air may not be noticeably heated in its downward course. By this means, loss of heat into the furnace room is prevented.

Standing upright and extending diametrically across the frusto cone-shaped section of the lining 26 is a one-piece sheet metal partition 28 whose opposite ends are inclined and bent laterally to form attaching flanges 28^a contacting with said section and secured 30 thereto. Disposed one pair on each side of the partition 28 are two pairs of radially positioned upright partitions 28^b, each pair of such partitions being formed by bending a single sheet of metal into V-shape as shown clearly in Figs. 3 and 4. The corner of each of these V-shaped formations is flattened as shown at 28^c, such flattened portion contacting with opposite sides of the partition 28 at the center thereof and being secured 35 thereto by bolts or the like 28^d, the latter passing through said portions and through said partition as shown. The outer ends of the partitions 28^b are inclined and bent laterally to form attaching flanges 28^e 40 contacting with and secured to the aforesaid frusto cone-shaped section of the lining 26. This construction, although simple and inexpensive, will be efficient and durable. By securing the ends of the partitions to the lining, expansion and contraction of said partitions under changes in temperature will be readily allowed since said lining is 45 spaced from the inner shell and may thus yield for this purpose. The formations just described constitute a plurality of segmental heat pockets having constantly open unobstructed lower ends disposed immediately above the furnace proper. Usually, the upper ends of such pockets will be equipped 50 with vertically swinging top plates 29 dis-

posed between the upper edges of adjacent partitions and preferably mounted upon horizontal rods 30 whose opposite ends are journaled in such edges. If such plates be provided, pulleys or other appropriate guides 31 will be placed at substantially the points of intersection of the several partitions, and chains or other cable members 32 will be secured to the inner ends of the plates 29, will be trained upwardly over the 55 guides or pulleys, and will be passed through openings in the numerous shells to the exterior of the casing as shown in Fig. 1, whereby any or all of the plates 29 may be raised or lowered at will. 60

In some cases, the removable pivotally mounted top plates 29 may be replaced by rigidly supported removable plates such as those disclosed at 30^a in Figs. 8, 9 and 10, such plates being provided with downwardly opening crimps 30^b receiving therein the upper edges of the several partitions, and being secured in position by bolts or the like 30^c. 65

Whether the plates 30 or 30^a be provided, when disposed to horizontal position, such plates are designed to normally prevent the escape of heated air through the upper ends of the dome-like pockets, said air however, being designed to pass from the furnace 95 through a number of discharge pipes 33 which extend outwardly one from each pocket and which are adapted to be connected with other appropriate pipes which may lead to suitable registers or the like disposed in the several rooms in the building to be heated, more particularly in the rooms on the upper floors, since the lower floor will be effectively heated by radiating heat from the furnace proper, which will rise through 100 the grating 21. The amount of heat rising through such grating, may be increased at will by removing the top plates 30 or 30^a, but it will be evident that as long as such plates are disposed horizontally as seen at 110 the left of Fig. 2, an equal amount of heat will flow from each pocket to a corresponding room. 115

The furnace proper 5 is shown in the present embodiment of the invention as provided with an updraft outlet pipe 34 and a down-draft outlet 34^a, both of these pipes being preferable, for reasons well known to those skilled in the art to which the invention relates. The two pipes 34 and 34^a pass loosely 120 through aligned openings in the shell and jacket and in the lining of said shell, and are surrounded by collars 35 and 35^a which abut the exterior of the jacket. To retain these collars in position, the construction 125 seen more particularly in Figs. 5 and 6 is provided. This construction comprises a pair of hook shanks 36 which are formed integrally with opposite edges of the opening in the jacket through which the pipe 34 130

passes, and an additional pair of such shanks 36^a which are formed integrally with the opening in the jacket receiving the downdraft pipe 34^a.

- 5 The shanks 36 and 36^a extend respectively to points between the collar 35 and the pipe 34 and between the collar 35^a and the pipe 34^a, the free ends of the shanks 36 and 36^a being bent laterally to provide respectively
- 10 hook bills 37 and 37^a which receive therein the inner edges of the collars 35 and 35^a. By this means, the collars are effectively held in proper relation in respect to the pipes which they surround, and in respect to
- 15 the outer shell and by so doing, further escape of heat at these points is prevented.

From the foregoing description, taken in connection with the accompanying drawings, the construction, manner of operation, 20 and the numerous advantageous features of the invention will be readily understood without requiring a more extended explanation.

Although, in the drawings I have shown 25 certain specific details of construction and in the preceding, have described such details, it is obvious that I need not be limited thereto otherwise than to the extent to which the appended claims restrict me.

30 I claim:

1. In combination, a furnace proper, a substantially cylindrical shell surrounding the same, rising therefrom, and having an open upper end provided with a horizontal grating, a plurality of upright radially located partitions in the shell between the furnace proper and the grating, said partitions meeting each other at a central point and extending to the shell to provide a plurality 35 of segmental heat pockets, the latter having constantly open unobstructed lower ends disposed immediately above the furnace proper, removable segmental top plates for closing or opening the upper ends of said 40 pockets to either allow or obstruct the passage of heat therefrom through the grating, and independent heat outlets leading from the pockets beyond the exterior of the shell.
- 50 2. In combination, an upright shell comprising a body portion of cylindrical formation, a frusto cone-shaped section rising therefrom, and a cylindrical upper section rising from said frusto cone-shaped section, 55 a grate at the upper end of said upper section, an upstanding one-piece sheet metal partition extending diametrically across the aforesaid frusto cone-shaped section of the shell and having inclined ends bent laterally 60 and forming attaching flanges, two pairs of radially located partitions disposed one pair

on each side of the first named partition, each of said pairs being formed of a single sheet of metal bent into the form of a V with its ends inclined and bent laterally to 65 form attaching flanges, the corners of the V-shaped formations being flattened and disposed in contact with opposite sides of said first named partition at the center thereof, bolts passed through said flattened 70 corners and through the intervening partition, removable segmental cover plates positioned horizontally and filling the spaces between the upper edges of the numerous partitions, whereby to form therewith heat 75 pockets, independent hot air outlets leading from such pockets beyond the exterior of the shell, means for admitting air into the lower end of said shell, and a furnace in said shell below the partitions. 80

3. In combination, an upright shell comprising a body portion of cylindrical formation, a frusto cone-shaped section rising therefrom, and a cylindrical upper section rising from said frusto cone-shaped section, 85 a grate at the upper end of said upper section, a lining in the shell including a frusto cone-shaped section disposed within and spaced from the frusto cone-shaped section of said shell, an upstanding one-piece sheet 90 metal partition extending diametrically across said section of the lining and having inclined ends bent laterally and forming attaching flanges secured to such section, two pairs of radially located partitions disposed 95 one pair on each side of the first named partition, each of said pairs being formed of a single sheet of metal bent into the form of a V with its ends inclined and bent laterally to form attaching flanges secured to 100 the aforesaid lining section, the corners of the V-shaped formations being flattened and disposed in contact with opposite sides of said first named partition at the center thereof, bolts passed through said flattened 105 corners and through the intervening partition, removable segmental cover plates positioned horizontally and filling the spaces between the upper edges of the numerous partitions, whereby to form therewith heat 110 pockets, independent hot air outlets leading from such pockets beyond the exterior of the shell, means for admitting air into the lower end of said shell, and a furnace in said shell below the partitions. 115

In testimony whereof I have hereunto set my hand in presence of two subscribing witnesses.

ARTHUR SCHIMMEL.
